UNITED STATES PATENT OFFICE.

EDWIN B. STIMPSON, OF BROOKLYN, NEW YORK, ASSIGNOR TO EDWIN B. STIMPSON COMPANY, OF BROOKLYN, NEW YORK.

RIVET-SETTING MACHINE.

Application filed July 8, 1921. Serial No. 483,354.

To all whom it may concern:

Be it known that I, EDWIN B. STIMPSON, a citizen of the United States, residing at Brooklyn, in the county of Kings and State of New York, have invented certain new and useful Improvements in Rivet-Setting Machines, of which the following is a specification.

This invention relates to machines for setting rivets or the like in leather or other sheet material, such machines including, as usual, a hopper, and a raceway down which rivets are fed to a cut-off and transfer slide which delivers them one by one to a pocket or holder, whence the individual rivet is driven through a sheet of leather or other material. In such machines the lower end of the raceway has generally been made by affixing strips of steel to the outer face of a stationary part fast to or integral with the machine head, with a unitary nose-piece fast to the face of the stationary part, having a rivet-guiding groove non-alined with the main raceway, the nose-piece having another groove extending horizontally and intersecting the rivet-guiding groove, and a slide in the horizontal groove adapted to be moved into alinement with and to receive a single rivet from the raceway proper, and then to be moved into alinement with and transfer the rivet to the rivet-guiding groove of the nose, whence the rivet drops into the carrier, immediately below a driver or plunger.

The slide referred to is reciprocated by means of a connection with some suitable moving part of the machine, in properly timed relation to the plunger which sets the rivets, and its well understood function is to receive and deliver one rivet at a time from the main raceway to the non-alined discharge raceway whence it goes to the pocket for the actual setting operation, the main raceway being in the meantime blocked off. Inasmuch as this slide is sometimes jammed by reason of rivets assuming wrong positions, or because a rivet may be defective or distorted, it is desirable that there should be, somewhere in the operative connection between the slide and the moving part of the machine through which it is reciprocated, a yielding element, one which is sufficiently rigid for normal operation, and which will yield and prevent breakage in case the slide is jammed.

It is an object of my invention to provide such a yielding connection in the form of a spring of special construction and having a particular relation to the parts which are connected by it, and which will secure the object above mentioned.

Other objects and aims of the invention, more or less broad than those stated above, together with the advantages inherent, will be in part obvious and in part specifically referred to in the course of the following description of the elements, combinations, arrangements of parts, and applications of principles constituting the invention; and the scope of protection contemplated will appear from the claims.

In the accompanying drawings, which are to be taken as part of this specification, and in which I have shown merely a preferred form of embodiment of invention:

Figure 1 is an elevation of a rivet setting machine embodying my invention;

Figure 2 is a detail of the slide operating parts, as in the Figure 1 relation;

Figure 3 is a view similar to Figure 2, showing what happens to the spring element when the operating lever moves and the slide is jammed; and

Figures 4 and 5 are top plan views of two slightly different forms of spring connection.

Referring to the numerals on the drawings, the hopper of a rivet setting machine appears at 6, and includes a rotating magazine 7, operated by means of a pawl 8, ratchet 9, pivoted link 10 and lever 11. Lever 11 also operates plunger 12, and link 10 is operatively connected with a pivoted lever 14. A main raceway from the magazine is indicated at 15, a discharge raceway section 16 alined with the main raceway, and a transfer and cut-off slide 17 which reciprocates between the two raceway sections. Reciprocation of the slide 17 in accordance with the oscillations of lever 14 takes place by reason of the spring connection 18 interposed between the slide and the lever. In making this spring connection I may take a length of suitably stiff wire or rod, and bend it upon itself, preferably so that it has a number of parallel courses 19 and terminal portions 20, the latter being secured to lever 14 and slide 17. The spring as a whole may be in substantially a single

plane (Figure 4), or, after being formed as in Figure 4, the courses 19 thereof may be curved as in Figure 5. In the latter case I am able to provide a spring of the same maximum vertical and horizontal straight line dimensions, with substantially the same normal rigidity as the Figure 4 form, but with greater elastic capacity because the actual length of the wire in 10 the spring from end to end will be greater in the Figure 5 construction even with identical maximum vertical and horizontal dimensions. The curvature of the plane of 15 the spring enables it to approach closer to the machine without contacting therewith and without diminution of elastic capacity.

Preferably the spring is so connected that its plane is the plane of movement of slide 17 or lever 14, or both in case the latter two 20 parts move in the same plane. If the slide and lever do not move in the same plane, the plane of the spring will correspond to the plane of movement of one of them, say the slide, and the upper part of the spring bent 25 away to meet the lever 14. The same remarks apply to the Figure 5 form, the plane of the spring in that case being the plane which includes the chords of the transversely curved courses 19.

30 The spring thus described has ample rigidity under normal conditions, and withal is sufficiently yielding so that it may be readily assembled in position, and so that in case of a jam the force of lever 14 will be 35 taken up in a distortion of the spring (Figure 3) without injury to the slide 17 or other parts.

Inasmuch as many changes could be made in the above construction, and many apparently widely different embodiments of 40 my invention could be made without departing from the scope thereof, it is intended that all matter contained in the above description or shown in the accompanying drawings shall be interpreted as illustrated 45 and not in a limiting sense.

It is also to be understood that the language used in the following claims is intended to cover all the generic and specific 50 features of the invention herein described and all statements of the invention which, as a matter of language, might be said to fall therebetween.

I claim:

55 1. In a device of the kind described, a reciprocating slide and a member for moving the same, and a resilient connection between said two parts comprising a spring made of a single length of wire or rod bent upon itself to form courses and terminal portions, all in substantially the same plane, said terminal portions being connected to the slide and to the moving element respectively, with the plane of the spring extending substantially in the line of movement of the slide

and said courses being substantially equal in length to the distance between said slide and said moving element.

2. In a device of the class described, a reciprocating slide member, a power-transmitting spring connected to one end of the slide member, said power-transmitting spring extending laterally with relation to the path of movement of the slide member and including undulations extending in substantially parallel relation to the path of movement of the slide, and a driving member connected to the other end of the power-transmitting spring to operate the spring to reciprocate the slide, said undulations in 80 said spring being substantially equal in length to the distance between said slide member and said driving member.

3. In a device of the class described, an elongated reciprocating slide member having an opening therein adjacent one end thereof, a power-transmitting spring having oppositely extending terminal portions, one of said terminal portions substantially fitting said opening and adapted to be readily inserted therein or removed therefrom, said power-transmitting spring extending laterally with relation to the path of movement of the slide member and including undulations extending in substantially parallel relation to the path of movement of the slide member, said undulations being distributed along the axis connecting the terminal portions of said spring, and a rock arm having movement substantially parallel to the path of movement of the slide and having an opening to receive the other terminal of the spring.

4. In a device of the class described, a slide member, a power-transmitting spring operatively connected with said slide member, and a driving member connected to the spring and spaced laterally with relation to the path of movement of the slide member, said power-transmitting spring being formed in undulations extending transversely to a line joining the points of connection of the spring with the slide member and the driving member, and said undulations being substantially equal in length to the distance between said members and lying substantially in the plane of movement of the spring and the slide.

5. In a device of the class described, a movable driving member, a power-transmitting spring having undulations extending transversely to the length of the spring and the length of the individual undulations being equal to at least one half the length of the spring and a driven member operated by said power-transmitting spring.

6. A power-transmitting member comprising a spring having transverse undulations equal in length to at least one half the length of the spring, and the spring as a whole be-

ing transversely curved, a driving member connected to one end of said spring and operating to move the spring in the directions in which the undulations extend, and
5 a driven member connected to the other end of the power-transmitting spring.

7. In a rivet-feeding machine, a reciprocating slide and a member for moving the same, and a resilient connection between
10 said two parts comprising a spring made of a single length of resilient material bent

upon itself to form courses and terminal portions, all in substantially the same plane, said terminal portions being connected to the slide and to the moving element respectively, the plane of said spring being curved to permit said spring to approach close to said machine, the plane of said spring extending substantially in the line of movement of said slide. 15

In testimony whereof I affix my signature.
EDWIN B. STIMPSON. 20
